DESIGN FOR A FOLDING STROLLER

Louis Kolker, Elizabeth, N. J.

Application June 8, 1943, Serial No. 110,400

Term of patent 3½ years

To all whom it may concern:

Be it known that I, Louis Kolker, a citizen of the United States, residing at 48 Hillside Road, in the city of Elizabeth, in the county of Union and State of New Jersey, have invented a new, original, and ornamental Design for a Folding Stroller, of which the following is a specification, reference being had to the accompanying drawings, forming part thereof.

In the drawings:

Figure 1 is a front elevational view of a folding stroller, showing my new design;

Figure 2 is a side elevational view; and

Figure 3 is a top plan view thereof.

I claim:

The ornamental design for a folding stroller, as shown.

LOUIS KOLKER.
